PANEL CONSTRUCTION

Garth G. Gilpin, Riverside, Ill., assignor to
 Standard Railway Equipment Manufacturing
 Company, Chicago, Ill., a corporation of Dela-
 ware

Application February 17, 1938, Serial No. 190,913

9 Claims. (Cl. 105—409)

The invention relates to panels used particularly as parts of railway cars, such as end walls, side walls, roofs, floors, drop end gates for mill type gondola cars, bulkheads for refrigerator cars, 5 hatch plugs and side doors for box or automobile cars.

The object of the invention is to provide a panel comprising a metallic sheet formed with a plurality of substantially parallel corrugations extending between and to opposite edges of the sheet, which corrugations are formed in the metallic sheet by the folding process without stretching the metal. When the corrugations merge into the body part of the sheet the permissible stretch 10 of the metal used determines both the depth and closeness or proximity of the corrugations. By extending the corrugations to the edge of the sheet the corrugations may be made of any desired depth and may be positioned very close 15 to each other; thus materially increasing the strength of the corrugations as compared with a panel having corrugations merging into the metallic plate and, of course, materially increasing the strength of the panel as a whole. In such 20 a construction a relatively thin metallic plate or sheet may be used to obtain the same strength as a relatively thick plate formed with the corrugations terminating into the body of the plate because more metal may be positioned away from 25 the neutral axis of the structure and also because the material is not stretched in corrugating it.

A further object of the invention is to provide means to stiffen each of the above mentioned 30 edges of the corrugated metallic sheet by providing a member extending normally to the length of the corrugations and secured to such corrugations to form a beam so that a load imposed upon the corrugations is transmitted to such 35 stiffeners, and a further object of the invention is to associate such stiffeners with other parts of the railway car so that such load will be transferred from the stiffeners to the car structure.

A further object of the invention is to so form 40 such stiffener and secure it to the corrugated metallic sheet as to provide a box shape beam having great strength for the amount of material used, and a further object is to form the stiffener so 45 that it can be secured to the corrugated metallic plate to form a weatherproof structure.

A further object of the invention is to provide 50 the stiffener with a diagonally disposed scallop or serrated margin on each side of the corrugated plate and to secure such margins together through

the corrugated plate to provide cooperation therebetween in beam action.

In forming a metallic plate or metallic sheet with corrugations extending between opposite edges thereof, by the folding process, the plate 5 is alternately bent in opposite directions on substantially parallel lines, and owing to the various stiffnesses of various metallic plates (of the same metal) and owing to the various degrees of stiffness in the same metallic sheet (due to the varying chemical composition of the metal) the several corrugations will not be exactly the same depth, nor will the distances between the several corrugations in the same plate be the same in 10 all cases, therefore, I position the serrations or scallops at an oblique angle to the plane of the panel so that as the stiffener is assembled with the corrugated plate these scallops or serrations will readily adjust themselves to the variations 15 in the contour of the several corrugations due to the fact that the angularity of the several serrations or scallops may differ relative to each other according to the difference in depth or width of the corrugations. This difference in 20 angularity may be small so it will not affect the 25 appearance of the finished panel, but, nevertheless, a tight fit between the serrations or scallops and the corrugated plate is essential so that the 30 several elements will cooperate mechanically, and secondly, so that welded material may be applied 35 at the edges of the serrations and the scallops, and thirdly, to provide a weatherproof structure.

Another object is to form the serrations or scallops described in the preceding paragraph in a semi-spherical surface so that as a scallop or 40 serration is pressed into place it will expand or contract to accommodate the variation in distances between adjacent corrugations and the variations in depths of the corrugations. The semi-spherical planes may be concave or convex. 45

The permissible variation in the angularity of the several scallops or serrations and the provision of semi-spherical scallops or serrations provides a contact between the edges of the scallops or serrations and the corrugations in the 45 metallic plate so that welded material may be easily applied to secure the edges of the scallops or serrations to the corrugations. This is important because welded material cannot be economically applied unless the materials are substantially in contact.

Another object is to provide means to stiffen 50 the edges of a metallic plate or sheet which has been strengthened and reinforced by a plurality of corrugations, as disclosed and claimed in Patent 55

No. 1,638,172 of August 9, 1927, and No. 1,681,818 of August 21, 1928, so that such reinforced and stiffened plate may be used as a panel or unit for parts of a railway car which are not rigidly fastened to other parts of the car, such, for instance, as drop end gates for mill type gondolas; drop doors; bulkheads for refrigerator cars and sliding side doors for box cars. In some devices it may be necessary, or desirable, to provide scallops or serrations on one side only of the corrugated plate, as, for instance, when the panel is used as a hopper door in a hopper car the scallops may be used on the upper side only; that is, the side in contact with the lading, to obtain free discharge of the lading, and also when the panel is used as a sliding side door for a box car the scallops may be used on the outside only to reduce wind resistance. When used as side wall units of a hopper car the scallops would be on the inside to assure discharge of the lading.

In the drawings:

Fig. 1 shows one-half of my improved panel.

Fig. 2 is a side view of Fig. 1.

Fig. 3 is a section on line 3—3 of Fig. 1.

Fig. 4 is a section on line 4—4 of Fig. 1.

Fig. 5 is an end view of Fig. 1.

Fig. 6 is a section on line 6—6 of Fig. 1.

Fig. 7 is a section on line 7—7 of Fig. 1.

Fig. 8 shows a front elevation of a railway car 30 wherein my improved panel forms the end wall thereof.

Fig. 9 shows a section on line 9—9 of Fig. 8.

Fig. 10 is a partial side elevation of the car shown in Figs. 8 and 9.

35 Figs. 11 to 16 inclusive show a plurality of my improved panels integrally connected to form walls, floors or roofs.

Figs. 1 to 7 inclusive show my improved panel wherein the metallic sheet 2 is formed with a 40 plurality of corrugations 3 comprising crests 4, valleys 5 and side walls 6, which corrugations 3 extend to the opposite edges 7 of the metallic sheet. The corrugations may be parallel and of equal width and equal depth. In the form illustrated I have shown relatively deep major corrugations 10 which decrease in depth and width toward the edges 7 of the plate in combination with a plurality of minor corrugations 11 positioned between the major corrugations 10 which 45 increase in width and depth toward the edges 7 of the plate, thus obtaining a plate of relatively great strength and rigidity adjacent the middle of the plate and relatively great resiliency adjacent the edges of the plate. At the edges 7 of 50 the plate the corrugations are preferably of equal depth and spaced apart distances equal their widths. These varying depth and varying width corrugations 10—11 are preferably positioned and formed so that the length of the center line of 55 the material at any cross section (normal to the corrugations) is substantially the same as any cross section parallel thereto, so that the opposite edges 7—7 are straight, parallel and normal to the length of the corrugations, thus 60 facilitating the application of my improved stiffeners. Such varying depth and varying width corrugations are disclosed in Patents No. 1,638,172 65 and No. 1,681,818 mentioned before.

The means shown for stiffening each edge 7 70 of the corrugated sheet comprises a channel shape stiffener 15 having a web 16 and spaced apart flanges 17 wherein the flanges 17 overlap and are preferably secured (18) to the ends of the corrugations 3 and wherein the margin of 75 each flange 17 comprises a plurality of diagonally

disposed scallops or serrations 20 extending between and preferably secured to the crests 4, valleys 5 and side walls 6 of the corrugations 3. Welded material is preferably applied at the edge of the scallops 20 to secure them to the adjacent corrugations. The scallops or serrations are diagonally disposed or positioned at an angle to the plane of the plate for reasons hereinbefore mentioned.

The opposite scallops or serrations 20 and 21 10 are positioned so that the planes thereof intersect and means are provided (preferably welded material) to secure such scallops or serrations to the corrugated sheet at the line of intersection of such planes to form a box structural stiffener. 15 These planes may be flat or semi-spherical, as heretofore mentioned, and as shown clearly in Figs. 2, 3 and 4.

Figs. 8, 9 and 10 show my improved panel forming the end wall of a gondola car wherein the 20 stiffener 30 comprises an outer member 31 secured to the side wall 32 of the car and overlapping the ends of the corrugations 3 secured thereto (33), which outer member 31 is provided with scallops or serrations 20. The inner member 36 is secured 25 to the side wall 32 of the car and underlies the end of the corrugations 3 and is preferably secured thereto (37), which inner member 36 is also provided with scallops or serrations 21. Welded material is preferably applied at the edge 30 of the scallops 20 and 21 to secure them to the adjacent corrugations.

Panels may be made with stiffeners having scallops or serrations on one side of the corrugated plate only and still come within the 35 scope of the invention.

Figs. 11 to 16 inclusive show my improved means of stiffening the edges of corrugated metallic sheets (wherein the corrugations extend to the edge of the sheet) wherein such means is also 40 used to connect the adjacent edges of such metallic sheets. Such connecting and stiffening means may form a post of a wall when the planes of corrugated sheets are vertically disposed. Such means may constitute a carline of a roof 45 structure or a rafter of a floor structure. The adjacent corrugated metallic sheets may be in the same plane, as shown in Figs. 11, 13 and 15, or the planes of the respective sheets may be angularly disposed, as shown in Figs. 12, 14 and 50 16, in which case, the means of stiffening and connecting the corrugated metallic sheet may form corner posts or eave mouldings.

In the construction shown in Fig. 11 the member 40 is positioned on one side of the corrugated metallic sheets 41 and 42 and overlaps and is secured to the metallic sheets by the welded material 43 and 44. The opposite margins of the member are each provided with a plurality of diagonally disposed scallops 45—46 which extend 55 between and are secured by welding 47—48 to the corrugations in the adjacent metallic sheet, as and for the purpose, heretofore described. The element 49 is positioned on the opposite sides of the sheets 41—42 from the member 40, which element overlaps the corrugations in both metallic sheets and is secured thereto preferably by the welded material 50—51. Fig. 12 shows a construction similar to Fig. 11 wherein the sheets 54 and 55 are disposed angularly to each other and the element 56 has angularly disposed arms 57 and 58 secured (59 and 60) to the respective sheets 54—55. The member 62 is preferably formed on a large radius to form an arch.

In Fig. 13 the construction is similar to Fig. 11, 75

but shows the outer member 66 flat and the inner element 67 serrated or scalloped. Fig. 14 shows the sheets 54 and 55 are disposed angularly to each other and the serrated or scalloped inner element 68 is flat.

In Fig. 15 the outer member 70 and the inner element 71, are both provided with opposite serrated or scalloped margins fitting within and secured to the corrugations of both of the corrugated metallic sheets 41—42. Fig. 16 shows a construction similar to Fig. 15 wherein the sheets 54 and 55 are disposed angularly to each other. In this arrangement the inner element 73 is flat.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. Means for stiffening the edge of a corrugated metallic sheet adapted for use as an end gate of a railway car wherein the corrugations extend to the edge of the sheet comprising a channel shaped stiffener with the flanges thereof overlapping the end portions of the corrugations, one of said flanges having a diagonally disposed margin formed with scallops which nest in and are rigidly secured along the edges thereof to the crests and troughs of said corrugations.

2. Means for stiffening the edge of a corrugated metallic sheet wherein the corrugations extend to the edge of the sheet comprising a channel shaped stiffener with the flanges thereof overlapping the ends of the corrugations, each of said flanges having a diagonally disposed scalloped margin extending between and secured to said corrugations, said scalloped margins positioned so that the planes thereof intersect, and means to secure said scalloped margins to the corrugated sheet at the line of intersection of said planes to form a box sectional stiffener.

3. Means for stiffening the edge of a corrugated metallic sheet adapted for use as an end gate of a railway car wherein the corrugations extend to the edge of the sheet comprising a channel shaped stiffener with the flanges thereof overlapping the end portions of the corrugations, one of said flanges having a diagonally disposed margin formed with scallops which nest in and are rigidly secured along the edges thereof to the crests and troughs of said corrugations, each scallop of the scalloped margin being a semi-spherical surface for the purpose specified.

4. Means for stiffening the edge of a corrugated metallic sheet adapted for use as an end gate of a railway car wherein the corrugations

extend to the edge of the sheet comprising a channel shaped stiffener with the flanges thereof overlapping the end portions of the corrugations, one of said flanges having a diagonally disposed margin formed with scallops which nest in and are rigidly secured continuously along the edges thereof to the crests and troughs of said corrugations.

5. Means for stiffening the edge of a corrugated metallic sheet adapted for use as an end gate of a railway car wherein the corrugations extend to the edge of the sheet comprising a channel shaped stiffener with the flanges thereof of overlapping and secured to the end portions of the corrugations, one of said flanges having a diagonally disposed margin formed with scallops which nest in and are rigidly secured along the edges thereof to the crests and troughs of said corrugations.

6. Means for stiffening the edge of a corrugated sheet adapted for use as an end gate of a railway car wherein the corrugations extend to the edge of the sheet comprising a channel-shaped stiffener with the flanges thereof overlapping the end portions of the corrugations and diagonally disposed scallops on said flanges which nest in and are rigidly secured along the edges thereof to the crests and troughs of said corrugations on opposite sides of said sheet.

7. Means for stiffening the edge of a corrugated sheet adapted for use as an end gate of a railway car wherein the corrugations extend to the edge of the sheet comprising a stiffener traversing said corrugations near the ends thereof and scallops on said stiffener which nest in and are rigidly secured along the edges thereof to the crests and troughs of said corrugations.

8. Means for stiffening the edge of a corrugated sheet adapted for use as an end gate of a railway car wherein the corrugations extend to the edge of the sheet comprising a stiffener traversing said corrugations near the ends thereof and diagonally disposed scallops on said stiffener which nest in and are rigidly secured along the edges thereof to the crests and troughs of said corrugations.

9. Means for stiffening the edge of a corrugated sheet adapted for use as an end gate of a railway car wherein the corrugations extend to the edge of the sheet comprising a stiffener traversing said corrugations near the ends thereof in flatwise relation with the general plane of the sheet, said stiffener having an angularly disposed part for reinforcement thereof, and scallops on said stiffener which nest in and are rigidly secured along the edges thereof to the crests and troughs of said corrugations.

GARTH G. GILPIN.
